OIL WELL TOOL

James J. Santiago, Los Angeles, Calif., assignor
to John Grant, Los Angeles, Calif.

Application October 5, 1937, Serial No. 167,389

3 Claims. (Cl. 255—76)

This invention has to do generally with improvements in oil well tools having parts actuated by fluid pressure, for example mud laden circulating fluid pressure, and in which the parts are subjected to excessive and destructive wear because of the abrading action of the operating fluid flowing at substantial or high velocities. The invention may be typically illustrated and described with reference to wall scrapers of the type disclosed in United States Letters Patent No. 2,072,859, granted March 9, 1937, to John Grant on Wall scraper; and in its more specific aspects, the invention may be regarded as an improvement upon the wall scraper comprising the subject matter of said patent.

As indicated, in oil tools having fluid pressure actuated parts against which the operating fluid impinges, the solid particles in the fluid may severely abrade the surfaces of the parts, and frequently wear them to a degree of virtual destruction within short periods of time, especially where the fluid velocities are high. This is particularly true in tools, for example of the later described type, wherein the pressure fluid is utilized both to operate a movable part and also to circulate past and in contact therewith. The major object of my invention is to provide means whereby the necessary fluid pressure for operation of the part may be maintained, and at the same time the destructive velocity effect of the fluid stream dissipated before the stream strikes the surfaces subject to abrading wear.

As a typical and illustrative embodiment of the invention, I show one form in which the fluid pressure actuated part requiring protection against abrading action of the circulating fluid, comprises a plunger rod extending longitudinally within the bore of the tool through which a flow of circulating fluid is maintained around the outside of the rod. The latter is made responsive to circulating fluid pressure by applying to the rod a head having openings that pass the fluid, but which are restricted sufficiently to maintain a pressure differential required to move the rods and the rod actuated parts. The usual difficulty encountered is that the high velocity circulating fluid streams discharged through the openings in the head, tend to severely abrade the bore wall or surface of the rod, or both, thus requiring frequent replacements in addition to expense and inconvenience. In accordance with the invention, I provide an improved form of hollow head extending beyond the upper end of the rod, and having fluid passing openings or slots so arranged that the fluid streams passing

therethrough are caused to impinge convergently together, away from the bore wall, and preferably at substantially the axial center of the bore beyond the end of the rod. In this manner the velocity effects of the streams are dissipated by turbulent convergence within the head, so that the velocity of the fluid thence flowing downwardly outside and in contact with the surface of the rod is sufficiently reduced that no serious abrading action can occur.

The invention will be more fully understood and explained to better advantage by proceeding with a description of a typical form shown in the accompanying drawing, in which:

15 Fig. 1 is a longitudinal central section showing a wall scraper with the cutters in collapsed condition;

Fig. 2 is a similar view showing the cutters in expanded positions;

20 Figs. 3 and 4 are cross sections on lines 3—3 and 4—4, respectively, of Fig. 1; and

Fig. 5 is a sectional view looking upward on line 5—5 of Fig. 2.

The illustrated tool comprises a tubular body 10 into the box end 10a of which is threaded the pin 11a of the tool joint 11, the latter in turn being connected to the drill string on its lower end. The body carries a suitable cutting tool or bit 13 which is shown to be formed integrally with the body, although the particular manner of attaching the bit to the body may be a matter of preference. Cutters 14 are mounted within a transverse slot 15 in the body, the cutters consisting of blades lying along side each other, face to face, in the body slot and movable pivotally on the transverse pivot pin 16 between the collapsed position of Fig. 1 and the expanded position shown in Fig. 2. The ends 14a and the lower edges 14b of the blades, as viewed in open position, are beveled to provide sharp cutting edges, the bevels on the two blades being reversed, as illustrated, so that the bevels trail the cutting edges as the tool rotates. In fully expanded position, the cutters swing into engagement with body shoulders 17 at the upper end of slot 15, the shoulders serving as stops to limit the cutter swing and also to take the upward thrust transmitted through the cutter during operation. In their collapsed position, see Fig. 1, the cutters are swung into engagement with stop pins 18, see Fig. 4, having beveled ends 14a corresponding in angularity to the bevel at the cutter edges 14b, so that the cutters bear flatly against the pins.

45 The cutters are actuated in their expansive movement from the position of Fig. 1 to that of

Fig. 2, by fluid pressure applied to a plunger, generally indicated at 19, within bore 20 of the body. The portion 20a of the bore within the upper interior of the body is of comparatively large diameter and tapers at 20b below shoulder 21 to a relatively small diameter bore 20c. Angular grooves 22 are formed in the body at the lower end of bore 20c to provide downwardly flaring communications between the bore and the cutter containing slot 15. Circulating fluid is discharged into and through the body bores by way of the tool joint bore 11b and the tubular drill string 12.

The cutter actuating plunger 19 comprises a hollow head 23 having an upwardly tapered portion 23a carrying an eye 24 to receive a tool for removing the plunger from the body in disassembling the tool after pin 16 has been withdrawn to disconnect the cutters. The bottom of the hollow plunger head 23 is connected at 25, by screw-threads or other suitable means, with the upper end of the rod 26. The lower end of rod 26 is connected at 27 with a pair of links 28 which, in turn, are pivotally attached at 29 to one each of the cutters 14, the pivots 29 being offset sufficiently from the axial center of the body that downward movement of the links causes their respective cutters to swing oppositely as shown in Fig. 2. The connection at 27 between the plunger rod 26 and links 28 comprises a nut 30 threaded on the lower end of the rod and having a lower bifurcated portion 30a into which is inserted a pivot pin 31 passing through the links. Nut 30 may be substantially cylindric in shape (see Fig. 3), having a substantially sliding fit within bore 20c, and is provided with vertically extending channels or recesses 32 through which circulating fluid is discharged from bore 20c downwardly through grooves 22 into the upper end of slot 15.

In this manner, the circulating fluid is discharged substantially straight downward into the cutter slot so as to wash the cutters free of accumulated mud or sand in the vicinity of their pivotal mounting, and also to create an outward circulation through and beyond the sides of the slot. The body may also be provided with angularly inclined bores 35 pointing toward the outer extremities of the cutters 14 in expanded positions. Bores 35 thus serve to direct streams of circulating fluid from tapered portion 20b of the body bore outwardly against and in the immediate vicinity of the scraper ends 14a of the cutter blades, so as to effectively and continuously wash away the cuttings as they are formed.

With reference to bores 35, it should be mentioned that they may or may not be provided, since in some situations ample circulation may occur through passage 30a. Where the bores are provided, however, they preferably will be somewhat restricted, as shown so that the portion of circulating fluid discharged through passage 30a will be ample to thoroughly wash abrading particles from the links or cutters. Preferably I provide a washer 50, or the equivalent, about pin 16 between the cutters 14, and also space the links by thickening their inner faces at 28a at the pin 31 to correspond substantially with the thickness of washer 50, for the purpose of preventing the links from becoming damaged as a result of binding or wedging together in their pivotal movement.

The plunger 19 is pressed downwardly by the circulating fluid pressure to swing the cutters from collapsed to expanded positions, and the

cutters are returned to collapsed condition when the fluid pressure is relieved, by a coil spring 38 encircling the plunger rod and bearing against body shoulder 21 and the lower end of plunger head 23. As previously indicated, the plunger head is designed particularly to avoid any serious wear by abrasive action of the circulating fluid, on either the inner surface of the body bore wall 20a, or the outer surface of the plunger rod 26. A restricted flow of circulating fluid through the plunger head is maintained through a plurality of circularly arranged, vertically extending slots 37, for example four in number, the lower ends of which terminate at points spaced from the wall of the body bore 20a. The plunger head is proportioned so as to have a diameter sufficiently large that the total fluid pressure acting downwardly against it will operate the cutters 14 without the necessity for particularly high fluid pressures per unit area, and also to enable the combined areas of slots 37 to be sufficiently large to avoid excessively high fluid velocities within the slots, and resultant abrasive wear. By giving the head a tapered or conical shape, I am able to provide both the desired effective plunger area and large total slot area.

Openings 38 are formed in the lower portion 23b of the head to pass fluid from chamber 39 downwardly into passage 40 between rod 26 and the bore wall. As shown in Fig. 5, openings 38 may, but not necessarily, directly underlie the slots 37, and are made comparatively large so as to offer little restriction to the fluid flow out of the head. The head 23 carries an annular packing ring 41 between slots 37 and openings 38, the packing being in engagement with the bore wall and preferably providing a substantially fluid-tight fit.

The circulating fluid entering chamber 39 within the hollow head through the elongated slots 37 is directed in downwardly and inwardly flowing streams that impinge against one another and come to a point of convergence at substantially the axial center of the body bore within the chamber. Preferably, the head will be sufficiently elongated, or the slots so arranged, that this point of impingement will be located at a point beyond the upper end of the rod 26, or above the lower end of the head. Upon converging within chamber 39, as indicated by the arrows, the circulating fluid streams mutually act to dissipate the increased velocity of the circulating fluid stream resulting from its passage through the slots. The result is a turbulent condition of flow within chamber 39, and a reduction in the fluid velocity to an extent that the fluid stream will not severely abrade any of the parts. And in addition, rod wear is further avoided by reason of the fact that the rod is not extended into the head, and therefore no high velocity or inwardly directed parts of the fluid stream strike the sides of the rod. As a result, the life of the plunger parts under surface conditions is greatly prolonged, to obvious advantage in obviating the necessity for frequent replacements or removal of the tool from the well for repair.

As I have mentioned, the drawings are to be regarded merely as illustrative of the invention in one of its typical and preferred forms, and various changes and modifications may be made without departure from the intended spirit and scope of the invention as defined in the claims.

I claim:

1. A well tool comprising a tubular body, a

cutter mounted in the body, a vertically extending cutter actuating plunger within the body bore and operable by fluid pressure, said plunger comprising a hollow head having an upper upwardly tapering portion and a rod operatively associated with the lower end of said head, there being a plurality of fluid passing slots in said tapered portion of the head arranged to direct streams of operating fluid to a point of convergence within the head above the upper end of the rod, the fluid thence passing downwardly through openings in the lower portion of the head into a space between said rod and the wall of said bore.

2. A well tool comprising a tubular body, a cutter mounted in the body, a vertically extending cutter actuating plunger within the body bore and operable by fluid pressure, said plunger comprising a hollow head having an upper upwardly tapering portion and a rod operatively associated with the lower end of said head, there being a plurality of fluid passing slots in said tapered portion of the head arranged to direct streams of operating fluid to a point of convergence within the head above the upper end of the rod, the fluid thence passing downwardly through openings in the lower portion of the head into a space between said rod and the wall of said bore,

and annular packing carried by said head between said slots and openings and engaging the bore wall.

3. In a hydraulically actuated well tool, a body having a vertical plunger receiving bore adapted to be connected at its upper end to fluid circulating means, a cutter movably mounted on the body, a cutter actuating plunger in the bore, said plunger comprising an upper hollow head and a member connecting with the lower end of the head and extending down through the bore and operatively associated with the cutter and being of a cross sectional size substantially less than the bore cross-section, the upper wall of the hollow head having a plurality of restricted ports which converge toward each other to cause fluid streams passing therethrough to mutually impinge, the hollow interior of the head being unobstructed and of large cross-sectional area compared with the area of said restricted ports, relatively large ports in the head wall leading from its interior to deliver fluid therefrom into the space in said body bore below the head around the connecting member, and means for discharging fluid from said bore space.

JAMES J. SANTIAGO.
